UNITED STATES PATENT OFFICE.

HARVEY M. GILLESPIE, OF CHICAGO, ILLINOIS, ASSIGNOR TO THE P & M COMPANY, OF CHICAGO, ILLINOIS, A CORPORATION OF ILLINOIS.

RAIL-ANCHOR.

1,273,848.

Specification of Letters Patent. Patented July 30, 1918.

Application filed October 13, 1917. Serial No. 196,387.

To all whom it may concern:

Be it known that I, HARVEY M. GILLESPIE, a citizen of the United States, residing at 855 Webster avenue, Chicago, in the county 5 of Cook and State of Illinois, have invented certain new and useful Improvements in Rail-Anchors, of which the following is a specification.

My invention relates to devices for preventing the longitudinal creep of railroad rails, and has as its primary object to provide an improved device of this character which will grip with equal tenacity rails, the base flanges of which differ in width or 15 thickness.

In certain types of rail anchors spring action is relied upon to maintain a firm hold of the device on the rail. These devices, while being practical in connection with 20 perfectly formed rails, are not well adapted for use in connection with imperfectly formed rails, that is, rails which differ somewhat in the thickness or width of their base flanges. In devices relying upon spring 25 action to maintain the necessary grip of the device on the rail to resist the creeping action, any deviation from the standard contour involving a narrowing or thinning of the base flange, results necessarily in lessening 30 the effective grip of the device on the rail. It has been proposed to overcome this objection by providing means whereby the torsional strain on the spring element may be increased or diminished to adapt the device to rail bases of different contours. In 35 devices, such as last mentioned, any increase in the width of the rail base, such as results from the wearing away of the rolls employed in the manufacture of rails, makes 40 these devices unsuitable for application to rails of this kind. My invention provides a rail anchor which may be readily applied to perfectly formed rails of different standards, to rails which, due to corrosion or other 45 causes, have base flanges of less dimensions than the prescribed standard, or to rails, the base flanges of which are somewhat wider or thicker than the prescribed standards, due, for example, to the wearing away of 50 the rolls employed in their manufacture.

It is one of the objects of my invention to provide an improved device, of the spring type, which, under each of the above conditions, will take a biting hold on the vertical 55 edge of the base flange of the rail and also

grip with equal tenacity the upper and lower surfaces of the base flange of such rails.

A further object of the invention is to provide a rail anchor of the spring type in which the jaws of the device will take a 60 wedging grip on the base flanges of rails of different sizes and contour.

In the drawings I have illustrated my invention in connection with the form of rail anchor patented to D. F. and D. L. Vaughan 65 in United States Letters Patent No. 1,021,387, issued March 26, 1912, though it will be obvious that the principles disclosed might be embodied in other constructions.

The invention is illustrated in the accompanying drawings, wherein like characters of reference designate like parts, and where- 70 in—

Figure 1 is a plan view of a railroad rail with a device constructed in accordance 75 with my invention applied thereto.

Fig. 2 is a side view, in elevation, of the device shown in Fig. 1, the rail in this figure being shown in section.

Fig. 3 is an end view of the device illus- 80 trating the interlocking position of the spring member with the shoe when the device is applied to rails of maximum dimensions.

Figs. 4 and 5 are views similar to Fig. 3 85 illustrating the interlocking position of the spring member when the device is applied to rails of lesser dimension.

Fig. 6 is an end view of the device illus- 90 trating the manner in which it is applied to the rail.

Fig. 7 is a perspective view of the shoe member of my device.

Fig. 8 is a plan view, similar to Fig. 1, illustrating a modified form of the inven- 95 tion.

Fig. 9 is a side view of the device shown in Fig. 8, and

Fig. 10 is a view, in perspective, of the 100 spring member employed in the modified construction.

Referring to Figs. 1 to 7 inclusive, of the drawings, 10 designates a railroad rail and 11 one of the cross ties on which the rail is supported. The rail anchor is illustrated in 105 its operative position on the base flange of the rail 10 and consists of a shoe 12 formed to provide a jaw 13 which fits over one edge of the base flange of the rail in a manner to wedgingly grip the upper and lower surfaces 110

thereof, and a spring element which extends around the shoe member and engages the opposite edge of the rail base. The shoe is preferably made of malleable iron, or other suitable material, and is provided with a foot or tie-abutting member 14 which bears against one of the vertical faces of the tie 11. The spring element above referred to is designated in the drawings by the reference character 15, and consists of a spring bar having a hook or jaw 16 at one end which is adapted to fit over the edge of the base flange of the rail opposite the shoe member 12. The upper portion 17 of the jaw 16 is preferably bent so as to have an angular relation with respect to the body portion of the bar 15. The other end of the spring element is provided with an enlargement 18 which extends around the shoe member 12 and interlocks therewith in the manner hereinafter described. The portion of the bar 15 extending under the rail is preferably given a slight twist so that the normal position of the enlargement 18 will be oblique to the plane of the jaw 16. The shoe is formed with slots 19, 20, 21 adapted to receive the upper end of the enlargement 18. These slots are preferably made somewhat wider than the thickness of the spring member 15 so that the enlargement 18 may be readily inserted in the slots when the device is being applied to the rail. 22 designates a boss providing a support for the lower edge of the spring bar when this element is in its operative position, and also provides a suitable fulcrum point for the claw bar or wrench 23 (Fig. 6) which is preferably employed in applying this device to the rail, the wrench 23 being provided with a lug 23^a which bears on said boss. 24 is a cam surface on the shoe member and is adapted to bear against the inner vertical surface of the enlargement 18 in a manner to cause a movement of the spring bar 15 transversely of the rail when said bar is subjected to a torsional strain such as, for example, when the enlargement is moved from one interlocking position to another in the direction indicated by the feathered arrows 25 in Figs. 1 and 3.

Operation: The shoe 12 is driven on the rail in a position so that the foot 14 will bear against the vertical face of the tie and the jaw 16 of the spring member is engaged with the edge of the rail base opposite the shoe. The spring member, by means of the wrench 23 applied to the enlargement 18, is then twisted and raised so that the upper edge of the enlargement extends into one of the slots 19, 20 or 21. The particular slot in which the enlargement is inserted is dependent, of course, upon the size of the base flange of the rail. It will be apparent that by reason of the engagement of the cam surface 24 with the inner vertical edge 18 of

the spring member any rearward twisting movement of the spring, such as is indicated by feathered arrows in Figs. 1 and 3, will move the jaws 13 and 16 of the shoe and spring member, respectively, closer together 70 and thereby increase the gripping action of the device on the rail transversely of the rail base. For rails of maximum size the enlargement 18 will be engaged with the slot 19. For rails of smaller bases the enlargement may be engaged with either of the slots 20 or 21. In any of the above positions the vertical edge 26 of the jaw 16 will take a biting hold on the vertical edge of the rail base. The hook 17 of the jaw 16 80 being angularly disposed with respect to the body portion of the spring member, will yield if such yielding be necessary to permit the vertical edges of said jaw and rail to be brought into engagement.

In addition to the gripping action of the device on the rail transversely thereof, the tendency of the spring member to assume the normal position from which it was sprung by a torsion or twisting action when 90 being applied, will exert a downward pressure on the hook 17 against the inclined surface of the rail base in a manner to cause the edge of the hook to take a biting hold on said base. A reverse pressure upon the enlargement 18 is exerted against the walls 95 19^a, 20^a, 21^a, as the case may be.

In Figs. 8 to 10 inclusive is shown a modified construction. In this construction the upper portion 17^a of the jaw 16^a alines with 100 the other portion of the jaw instead of being angularly disposed thereto, as shown in the preceding figures. In this device the lateral movement of the spring member 15^a, due to the pressure of the cam surface 105 against the surface 27 of the enlargement 18, while the device is being applied to the rail, will cause an increased wedging engagement of the jaw 16^a with the flange, ^a of the rail. The torsional strain to which this device is subjected, when moving the enlargement into interlocking engagement with the shoe, will tilt the hook portion 17^a so as to cause the edge 28 of said hook portion to take a biting hold on the upper surface 110 of the rail. In other respects this device is made the same as that described in Figs. 1 to 7 inclusive, and the parts are given the same reference characters.

I am aware of the devices shown and described in the application of Philip W. Moore for improvements in rail anchors, Serial Number 169,934, filed May 21, 1917; I therefore do not claim broadly herein the subject-matter described and claimed in the above Moore application.

I claim:

1. A rail anchor comprising rail engaging jaw members, one being a spring, which are capable of different interlocking en- 130

gagements with each other whereby the distance between the jaws of said members may be varied.

2. A rail anchor comprising a shoe and a spring member provided with jaws adapted to engage opposite edges of the base flange of a rail which members are capable of different interlocking engagements with each other whereby the distance between said jaws may be varied.

3. A rail anchor comprising a shoe engaging one edge of the rail base and a spring member formed with a jaw adapted to engage the opposite edge of said base, said spring and shoe being adapted to have different interlocking engagements whereby the distance between said jaw and shoe may be varied.

4. A rail anchor comprising a shoe engaging one edge of the rail base and a spring member adapted to be subjected to a torsional strain and having different interlocking engagements with said shoe whereby the said spring may be subjected to a torsional strain and the distance between the jaw and said shoe varied to accommodate the anchor to rail bases of different thicknesses and widths.

5. A rail anchor comprising a shoe engaging one edge of the rail base and a spring member adapted to be subjected to a torsional strain and having different interlocking engagements with said shoe whereby the said spring may be subjected to torsional strains of different degrees, and the distance between the jaw and said shoe varied to accommodate the anchor to rail bases of different thicknesses and widths.

6. A rail anchor comprising a shoe element engaging one edge of the base flange and a spring element extending around said shoe and formed with a jaw engaging the opposite edge of the rail base and adapted to be subjected to a torsional strain, said elements being provided with means whereby different interlocking engagements with each other may be effected to subject said spring to torsional strains of different degree and vary the distance between said shoe and jaw.

7. A rail anchor comprising a shoe element engaging one edge of the base flange and a spring element extending around said shoe and formed with a jaw engaging the opposite edge of the rail base and adapted to be subjected to a torsional strain, said elements being provided with means whereby different interlocking engagements with each other may be effected, each of which subjects said spring to torsional strains of different degree and varies the distance between said shoe and jaw.

8. A rail anchor comprising a shoe element engaging one edge of the base flange and a spring element extending around said shoe and formed with a jaw engaging the

opposite edge of the rail base and adapted to be subjected to a torsional strain, said elements being provided with means whereby different interlocking engagements with each other may be effected, each of which subjects said spring to torsional strains of different degree and varies the distance between said shoe and jaw to accommodate the anchor to rail bases of different thickness and widths.

9. A rail anchor comprising a shoe and a spring member which together embrace the rail and which are capable of different interlocking engagements with each other to increase the grip of the anchor across the rail base from side to side thereof.

10. A rail anchor comprising a shoe and a spring member which together embrace the rail, said shoe being provided with a plurality of notches whereby the spring member may be subjected to torsional strain and interlocked therewith, and provided with means whereby the grip of said anchor on the rail may be increased across the rail base from side to side thereof.

11. A rail anchor comprising a shoe and a spring member which together embrace the rail, said shoe being provided with a plurality of notches whereby the spring member may be subjected to torsional strain and interlocked therewith, and provided with a cam surface whereby the grip of said anchor on the rail may be increased transversely of the rail.

12. A rail anchor comprising a shoe having a jaw adapted to fit over one edge of the base flange of a rail, and a flat spring having a hook adapted to engage the opposite edge of the rail base and provided at its opposite end with an enlargement; said shoe being formed with a plurality of stops adapted to be engaged by the enlargement of said spring so as to subject said spring to a torsional strain, and provided with a cam surface adapted to be engaged by said enlargement to increase the grip of the device transversely of the rail.

13. A rail anchor comprising a shoe having a jaw adapted to fit over one edge of the base flange of a rail, and a flat spring having an angularly disposed hook adapted to engage the opposite edge of the rail base and provided at its opposite end with an enlargement; said shoe being formed with a plurality of stops adapted to be engaged by the enlargement of said spring so as to subject said spring to a torsional strain, and provided with a cam surface adapted to be engaged by said enlargement to increase the grip of the device transversely of the rail.

14. A rail anchor comprising a shoe having a jaw adapted to fit over one edge of the base flange of a rail, and a flat spring having an angularly disposed hook adapted to engage the opposite edge of the rail base so

as to bear with spring pressure on the top of the flange, and provided at its opposite end with an enlargement; said shoe being formed with a plurality of stops adapted to be engaged by the enlargement of said spring so as to subject said spring to a torsional strain, and provided with a cam surface adapted to be engaged by said enlargement to increase the grip of the device transversely of the rail.

15. A rail anchor comprising a shoe having a jaw adapted to fit over one edge of the base flange of a rail, and a flat spring having an angularly disposed hook adapted to engage the opposite edge of the rail base so as to bear with spring pressure on the top of the flange, and provided at its opposite end with an enlargement; said shoe being formed with a plurality of stops adapted to be engaged by the enlargement of said spring so as to subject said spring to torsional strains of different degrees, and provided with a cam surface adapted to be engaged by said enlargement to increase the grip of the device transversely of the rail.

16. A rail anchor comprising a shoe having a jaw adapted to fit over one edge of the base flange of a rail, and a flat spring having an angularly disposed hook adapted to engage the opposite edge of the rail base so as

to bear with spring pressure on the top of the flange, and provided at its opposite end with an enlargement; said shoe being formed with a plurality of stops adapted to be engaged by the enlargement of said spring so as to subject said spring to torsional strains of different degrees to vary said spring pressure on said flange, and provided with a cam surface adapted to be engaged by said enlargement to increase the grip of the device transversely of the rail.

17. A rail anchor comprising a shoe having a jaw adapted to fit over one edge of the base flange of a rail, and a flat spring having an angularly disposed hook adapted to engage the opposite edge of the rail base so as to bear with spring pressure on the top of the flange, and provided at its opposite end with an enlargement, said shoe being formed with a plurality of stops adapted to be engaged by the enlargement of said spring so as to subject said spring to torsional strains of different degrees to vary said spring pressure on said flange, and provided with a cam surface adapted to be engaged by said enlargement to increase the grip of the device transversely of the rail as an increased torsional strain is applied to said spring member.

HARVEY M. GILLESPIE.
